S. S. MIDDLEBROOK, OF SANDY HOOK, CONNECTICUT.

Letters Patent No. 63,549, dated April 2, 1867.

HAT-BLOCKING MACHINE.

The Schedule referred to in these Letters Patent and making part of the same.

TO ALL WHOM IT MAY CONCERN:

Be it known that I, S. S. MIDDLEBROOK, of Sandy Hook, in the county of Fairfield, and State of Connecticut, have invented a new and improved Hat-Blocking Machine; and I do hereby declare that the following is a full, clear, and exact description thereof, which will enable others skilled in the art to make and use the same, reference being had to the accompanying drawings, forming part of this specification.

This invention relates to a machine by which the conical hat body is gradually transformed into a perfectly-shaped hat.

The machine consists of three distinct portions, through each of which the hat body is passed before its shape is perfected.

In the first machine the tip is stretched, that is to say, the conical hat body is placed upon a set of levers, the upper ends of which meet in one point, their bodies extending outwards, thus conforming to the conical shape of the hat body. The tops of the levers are then gradually moved from the centre, whereby the hat body is stretched out, receiving a somewhat cylindrical shape. The hat body, thus stretched, is then brought into the rim-stretcher, which consists of a pair of corrugated conical rollers, between which the rim of the hat is placed, and, by turning the rollers, the rim is so stretched that it will be flat when the hat is placed upon a table. In the third machine the crown of the hat is pressed into the required shape by a punch, which presses out the centre or crown of the hat. The hat is placed upon an India-rubber ring, the rim resting on the rubber, the crown extending down through a hole in the table, on which the rubber ring rests. The punch is then forced down and finishes the shape of the hat. In the accompanying drawings my invention is illustrated—

Figure 1 representing a plan or top view of the strip stretcher.

Figure 2 is a vertical longitudinal section of the same, taken on the line *x x*, fig. 1.

Figure 3 is a detail view of the levers on the tip-stretcher when the same are expanded.

Figure 4 is a front elevation of the rim-stretcher.

Figure 5 is a vertical longitudinal section of the same, taken on the line *y y*, fig. 4.

Figure 6 is a vertical longitudinal section of the "blocker," taken on the line *z z*, fig. 7.

Figure 7 is a vertical cross-section of the same, taken on the line *x' x'*, fig. 6.

Similar letters of reference indicate like parts.

A, figs. 2 and 3, represents a vertical shaft, which is rigidly secured to the platform B. On the top of the shaft A are secured arms or cross-heads C, to which are pivoted the levers D. *a* is an India-rubber ring, which encircles the lever D above their pivoting point, and by which the tops of the levers are made to meet at a common point. A treadle, E, is hinged on the platform B, and supports, by means of rods or bars *b*, a disk, F, which slides loosely on the shaft A, and which is pressed up by a spiral or other spring *c*. This disk F is slotted, as seen, so that the lower part of each lever will fit into one of the slots. These slots are closed on the outside by a metal band, *d*. The conical hat body is placed upon the cone, formed by the upper ends of the converging levers D. The treadle E is then pressed down; thereby the disk F is pulled down, the band *d* pressing against the outside of the levers D, pressing their lower ends together and spreading out their upper ends. The hat body is thus stretched as indicated in fig. 3. As soon as the pressure is removed from the treadle the action of the elastic ring *a* and spring *c* will at once bring all the parts into their original position again. The hat body is now brought to the rim-stretcher, which is illustrated in figs. 4 and 5. This consists of two corrugated conical rollers G and H, which mesh into each other. The roller G is secured to a horizontal shaft, *e*, and is revolved by means of a crank or pulley, *f*. The upper roller H is secured to a shaft, *g*, which is secured in a swinging frame, I, the latter being pivoted at *h* and adjusted by a set-screw, *i*, as seen, so that the rollers can be adjusted to hats of different thickness. The rim of the hat is inserted between the two rollers G and H in the manner shown in fig. 5. The rim is thereby stretched so that it will be flat and lie well on the table of the "blocker," to which the hat, thus far prepared, must be next transferred. The blocker, which is illustrated in figs. 6 and 7, consists of a frame, K, upon which is arranged a table or platform, L. The latter is provided with a round hole, as seen. Upon it is laid a rubber ring, M, which is held in position by a curl or hoop on the table. The hat is placed upon

the rubber ring, its crown passing down through the hole in the table, as indicated in fig. 6. A cross-head, *l*, is now pressed upon the rim of the hat, keeping the same steady, while the block or punch *N* is forced down into the hat, giving it the required shape. The rubber ring prevents the hat from slipping or drawing in with the block. The block *N* may be operated by connecting-rods *m*, which are worked by eccentric-cams *n* on a shaft, *o*. The cross-head *l* may be operated by rods *p*, which are worked by cams *q* on the same shaft *o*; but any other manner of raising or lowering the cross-head and the punch or block may be employed. After the rim of the hat is passed through the corrugated rollers it may be passed through a pair of smooth conical rollers to remove any wrinkles.

I claim as new, and desire to secure by Letters Patent—

1. The construction and arrangement of the vertical shaft *A*, lever *D*, cross-head *C*, rubber-ring *a*, perforated disk *F*, with its edge grooved to receive the metallic rod *d*, surrounding said levers *D*, as herein set forth for the purpose specified.
2. The conical corrugated rollers *G H*, the teeth of which mesh into each other, swinging-frame *I*, bearing the oblique shaft *g*, and pivoted at its outer end *h* to the frame, adjusted by means of the set-screw *i*, when constructed and arranged to operate as herein set forth for the purpose specified.
3. The rubber ring *M* upon the table *L* of the frame *K*, sliding cross-head *l*, and block *N*, when constructed and arranged to operate as herein set forth.

S. S. MIDDLEBROOK.
